CANDLESTICK OR SIMILAR ARTICLE

Howard Denby and Linda S. Denby, Chicago, Ill.

Application October 15, 1949, Serial No. 5,530

Term of patent 3½ years

(Cl. D48—2)

To all whom it may concern:

Be it known that we, Howard Denby and Linda S. Denby, both citizens of the United States, residing at Chicago, in the county of Cook and State of Illinois, have invented a new, original, and ornamental Design for Candlestick or Similar Article, of which the following is a specification, reference being had to the accompanying drawing, forming a part thereof, in which:

Fig. 1 shows a side elevational view of a candlestick in accordance with our novel design; and

Fig. 2 shows a plan view thereof.

We claim:

The ornamental design for a candlestick or similar article, substantially as shown.

HOWARD DENBY.
LINDA S. DENBY.
